UNITED STATES PATENT OFFICE.

WILLIAM W. WEHRLE, OF NEWARK, OHIO.

DESIGN FOR A COOKING-STOVE.

SPECIFICATION forming part of Design No. 29,394, dated September 20, 1898.

Application filed August 27, 1898. Serial No. 689,707. Term of patent 7 years.

To all whom it may concern:

Be it known that I, WILLIAM W. WEHRLE, a citizen of the United States, residing at Newark, in the county of Licking and State of Ohio, have invented and produced a new and original Design for Cooking Stoves or Ranges, of which the following is a specification, reference being had to the accompanying drawing, forming a part thereof.

10 In the drawing is shown a perspective elevation of a cooking stove or range which embodies my design as a whole.

Considering the features of the design severally, A represents the skirting about the bottom of the stove, which is relieved by a beaded and figured ornamentation a, blended in with the ornamentation on the legs a', and having a plain center a² on its sides and a like but reduced plain surface a³ centrally at 20 its ends.

B is the oven-door, which has a medallion b at its center and a special design of figure-work about it resembling somewhat a clover-leaf in outline, and at or near the corners of the door are plain raised surfaces b', which are surrounded by ornamentation which blends with the figure-work centrally of the door and makes a complete design in itself. The space between the skirting A and the 30 door B is further relieved by an ornamental shelf-like projection C, which in the stove itself is designed to be highly finished.

D represents the ornamentation on the end of the water-back, which is characterized by 35 the central raised plain surface d, circular in outline and having scrollwork about it, which is gathered up at one point and a trail of it thrown across the said plain surface d.

E is the stove-door, which enters the fire-pot and is decorated in harmony with the oven-door, having clover-leaf center e and scallops e' about the same, especially on one side.

F represents the front door, which has an 45 overhanging highly-finished and ornamented top portion f and a comparatively plain lower portion, which is relieved by a series of vertical openings f².

G is the support for the warming-oven.

This part of the design is especially prominent both in outline and ornamentation, having its surface elaborately covered with scroll-work g, wrought out in a harmonious combination and relieved by the two points or projections g' at either side or edge, which are 55 each surmounted by a disk-shaped member g². The support G is narrowest just opposite the said projections g' and widest beneath the same and widens gradually toward its top.

H is the warming-oven, having both its front 60 doors relieved with heavy scrolls h, lying lengthwise thereof, and about the top of the said oven is a heavy ornamental flaring border h'. The complete effect of the design as a whole is one of massiveness and richness 65 and withal attractive to the eye.

What I claim as new, and desire to secure by Letters Patent, is—

1. In a design for a cooking stove or range, the design for the skirting thereof, substantially as shown and described. 70

2. In a design for a cooking stove or range, the design for the oven-door, substantially as shown and described.

3. In a design for a cooking stove or range, 75 the design for the reservoir, substantially as shown and described.

4. In a design for a cooking stove or range, the design for the door of the fire-pot, substantially as shown and described. 80

5. In a design for a cooking stove or range, the design for the front door thereof, substantially as shown and described.

6. In a design for a cooking stove or range, 85 the design for the heating-oven, substantially as shown and described.

7. In a design for a cooking stove or range, the design for the support of the heating-oven, substantially as shown and described.

8. The design for a cooking stove or range, 90 substantially as shown and described.

Witness my hand to the foregoing specification this 6th day of August, 1898.

WILLIAM W. WEHRLE.

Witnesses:

E. M. BAUGHER,
JOHN MOSER.
